WILLIAM J. DESMOND, OF HARRISON, NEW JERSEY

DUPLEX ELECTRON-DISCHARGE DEVICE

Application filed August 1, 1924. Serial No. 729,472.

The object of the present invention is to provide an electron tube for radio use that will have a much longer useful life than the tubes of this character at present in use.

5 The tube comprises an evacuated envelope having a base at each end adapted to make external connections with the circuits of a radio receiving or transmitting set. Within the envelope are two stems for mounting the 10 electrodes, one stem being at each end of the tube. The electrodes consist of two filaments, one mounted on each stem; a single anode and a single control electrode each of which is provided with a double set of lead 15 wires one set being mounted on each stem and connecting into the appropriate external circuits through either base. Such a tube, being a duplex tube, is capable of being adjusted into the tube sockets of a radio set at 20 either end.

In order that the invention may be clearly understood, I have illustrated it by the accompanying drawings. Figure 1 shows the mounting of the filaments within the tube.

25 Figure 2 shows a detail of the construction representing the mounting of the two filaments upon their respective stems.

As will be evident from the drawing, there is a base with a full set of contact prongs at 30 each end of the closed envelope. It will also be evident that I have provided a stem at each end of the tube through each of which are sealed a full set of leads from the electrodes to the prongs of the base.

35 Referring to Figure 1, which shows the mounting of the filament, it will be noted that the stem A is set at an angle preferably at right angle to the stem A'. The filament leads B of the stem A are sealed through 40 the press of the stem and to this a filament which may be, as shown in the drawing, of the hair pin type, is welded. A similar construction of the filament leads B' is also shown. The filament D', which is welded 45 to the leads B' passes over the filament D so

that the loops or points of the hair pin filaments interlink without touching. The filament D is held taut by a hook C' which is sealed into the press of the stem A'. In like manner the filament D' is held taut by the 50 hook C which is sealed into the stem A.

The angular set of the glass stems permits the mounting of the hair pin filament in such a manner that the filament wires may interlink without interference with each 55 other.

The grid and plate are placed about the two filaments. I prefer to construct both of these electrodes in cylindrical form mounted coaxially, but I may employ any of the forms 60 at present in use. Lead in wires from these electrodes are sealed through each of the stems and extend to the posts or prongs of each base adapted to form external connections into the appropriate circuits of the radio apparatus. 65

When the tube so constructed is in use one base is fitted into the socket of the radio apparatus and the other base with its lead in wires is out of use. The advantage of this 70 invention consists primarily in the fact that the tube may be used on one base until the filament is burned out and it may then be reversed and the second filament be brought into use. The exposed prongs of the base 75 that is at any time turned upwards may, if desired, be covered with a plug of bakelite, rubber or similar insulating material.

In the drawings Figure 1 and Figure 2, I have shown one form of the tube only. It 80 will be evident, however, that other arrangements of the parts may be made without departing from the principle of this invention.

Having thus described my invention, what 85 I claim is:—

1. In an electron discharge device comprising a sealed evacuated glass envelope, having stem presses sealed into said envelope at opposite ends thereof, said stems being set 90

at an angle to each other but coincident with the longitudinal axis of the tube and each stem having a hair pin filament mounted thereon, the said filaments interlinking without interference with each other.

5 2. An electron discharge device having stem presses at opposite ends, the planes of which are at an angle to each other, a plurality of cold electrodes mounted in each 10 stem, a filament in each stem interlinked with the filament in the other stem and means to hold the filaments out of contact.

In testimony whereof, I have hereunto set my hand this 11th day of July, 1924.

15 WILLIAM J. DESMOND.
